CLAIM

The ornamental design for a shoe, as shown and described.

DESCRIPTION

FIG. 1 is a top right front perspective view of the shoe showing a first embodiment of our new design;

FIG. 2 is a bottom plan view thereof;

FIG. 3 is a rear elevational view thereof;

FIG. 4 is a front elevational view thereof;

FIG. 5 is a right side elevational view thereof;

FIG. 6 is a left side elevational view thereof; and

FIG. 7 is a top plan view thereof;

FIG. 8 is a top right front perspective view of the shoe showing a second embodiment of our new design;

FIG. 9 is a bottom plan view thereof;

FIG. 10 is a top rear perspective view thereof;

FIG. 11 is a top front perspective view thereof;

FIG. 12 is a top right side perspective view thereof;

FIG. 13 is a top left side perspective view thereof; and,

FIG. 14 is a top plan view thereof.

The broken lines depict portions of the shoe that form no part of the claimed design.

1 Claim, 14 Drawing Sheets
